CLAIM

We claim the ornamental design for a suspension culture device, as shown and described.

DESCRIPTION

FIG. 1 is a perspective view of the suspension culture device according to the invention;

FIG. 2 is another perspective view thereof;

FIG. 3 is a top view thereof;

FIG. 4 is a bottom view thereof;

FIG. 5 is a side view thereof;

FIG. 6 is another side view thereof;

FIG. 7 is another side view thereof;

FIG. 8 is another side view thereof; and,

FIG. 9 is another perspective view thereof.

The broken lines depict portions of the suspension culture device that form no part of the claimed design.

1 Claim, 6 Drawing Sheets
